UNITED STATES PATENT OFFICE.

BLOOMFIELD BROWER, OF NEW YORK, N. Y.

DESIGN FOR A PEN-RACK.

Specification forming part of Design No. 7,596, dated July 28, 1874; application filed July 13, 1874.
[Term of Patent 3½ years.]

To all whom it may concern:

Be it known that I, BLOOMFIELD BROWER, of city, county, and State of New York, have invented a Design for a Pen-Rack, of which the following is a specification:

The nature of my design is fully represented in the accompanying photographic illustration to which reference is made.

The distinctive features of my invention are, the form or design of the center piece A A A connecting the side pieces B B, rising from the front C C to and above the centers of the side pieces B B, and then descending at the back to the level of the front C C, and the form and design of the side pieces B B (excepting the recesses d d d, which are not new, and I do not claim them) rising from the front C C and projecting above and beyond connecting center pieces A A.

What I claim as my invention is—

The design for a pen-rack, consisting of the center piece A and connecting side pieces B, ornamented, as shown in the illustration.
